CARRIER FOR GOLF CLUBS

Isao Sasaki, Pasadena, Calif.

Application March 25, 1959, Serial No. 55,160

Term of patent 14 years

(Cl. D34—5)

Fig. 1 is a side elevation of a carrier for gold clubs, showing my new design;

Fig. 2 is a front elevational view thereof;

Fig. 3 is a top plan view of the carrier for golf clubs;

Fig. 4 is a plan section taken along line 4—4 of Fig. 2; and

Fig. 5 is a sectional elevation taken along line 5—5 of Fig. 3.

The broken line showing of a ball is for illustrative purposes only.

I claim:

The ornamental design for a carrier for golf clubs, as shown and described.
